UNITED STATES PATENT OFFICE.

COLEMAN MULFORD GRAY, OF DEL MAR, CALIFORNIA.

TUNING DEVICE FOR WIRELESS RECEIVING CIRCUITS.

Application filed August 15, 1921. Serial No. 492,385.

To all whom it may concern:

Be it known that I, COLEMAN M. GRAY, a citizen of the United States, residing at Del Mar, in the county of San Diego and State 5 of California, have invented new and useful Improvements in Tuning Devices for Wireless Receiving Circuits, of which the following is a specification.

This invention has reference to tuning devices for radio or wireless telegraphs, and its object is to provide tuning means of great delicacy and far more reliable in action than is customary, the action of the instrument being similar in minuteness of 15 adjustment to that of a vernier in conjunction with linear measurements, while retaining some of the features of the radio instrument known as the variometer.

In accordance with the invention, there 20 is provided a fixed coil in which there is mounted a movable coil rotatable in the axis of the fixed coil, and within the movable part and rotatable about the same axis as the latter there is mounted still another 25 coil which may participate in the movements of the second coil, or have a range of movement independently of the second coil. The arrangement is such that either the independent or the unison movement of 30 the third coil makes it possible to produce variations in effect of great minuteness, by advancing or retarding adjustments of the third coil with respect to the second coil and also with respect to the fixed coil.

The invention is based in part upon the 35 instrument known as the variometer and extensively used in radio circuits of all types, as sending, receiving, measuring, etc.

The variometer usually consists of two 40 coils, concentrically mounted and connected in series. The external coil, called the stator, is stationary, while the internal coil or rotor, is rotatable through an arc of 180°. When the rotor is at one end of its 45 travel, the direction of its winding is opposed to the winding of the stator and the inductance is at a minimum. When the rotor is at the other end of its travel, the direction of its winding is that of the stator, 50 and the inductance is at a maximum. At any intermediate position, the inductance will be a function of the angle of rotation.

It is usual to wind both the stator and the 55 rotor on spherical forms to thereby provide a minimum clearance between the two, and to employ a fairly large number of

turns of winding. Both of these forms of construction are necessary if the variometer is to cover a sufficiently broad band of inductance to render it useful as a tuning device.

The variometer, as described, forms one of the most delicate variable tuning devices heretofore known, and is further desirable in that it eliminates certain losses found in other types of variable inductances which need not be here described. However, since the introduction of continuous wave transmitting apparatus operating at very high frequencies (short wave lengths), it has been found that even the variometer as 65 usually constructed does not permit of sufficient delicacy of adjustment to give satisfactory tuning. If the variometer contains a large number of turns, its tuning range 70 will be broad, but its adjustment will be coarse. If it contains a relatively small number of turns the adjustment will be fine, but the tuning range is then impractically 75 small. A possible solution of this condition 80 is to place two variometers, one large and one small, in series but this brings about a needless complexity of apparatus and often presents undesirable electrical features.

The present invention, comprising a variometer with vernier adjustment, presents 85 a completely satisfactory solution of the problem. It consists of a standard variometer with a third coil, also rotatable, placed inside of the rotor and in inductive 90 relation to it.

This third or vernier coil is mounted on the same centers or axis as the rotor and may be turned with the rotor or turned 95 while the rotor remains stationary. The vernier coil need contain but a relatively small number of turns so that a large rotation of this coil with respect to the rotor creates but a small change in the total inductance of the device. The principle of 100 this vernier coil with respect to the rotor coil is the same as that of the rotor coil with respect to the stator coil. When the rotor and vernier coils lie in the same direction, inductance is at a maximum, and 105 when they lie in opposite directions, the inductance is at a minimum, while at any intermediate point the inductance will be a function of the angle of rotation.

The invention will be best understood 110 from a consideration of the following detailed description taken in connection with

the accompanying drawings forming a part of this specification with the understanding, that the invention is not confined to any strict conformity with the showing of the drawings but may be changed and modified so long as such changes and modifications mark no material departure from the salient features of the invention as expressed in the appended claims.

10 In the drawings:

Figure 1 is a diagrammatic perspective view of the invention with the coils displayed.

Figure 2 is an end view of the structure 15 of the invention.

Figure 3 is a cross section on the line 3—3 of Figure 2.

Figure 4 is a section on the line 4—4 of Figure 2.

20 Referring to the drawings, as shown in Figs. 2, 3, and 4, two blocks 1, 2, respectively, which may be made of wood or other suitable material, are indicated as of rectangular outline. These blocks together constitute the body of the instrument and each block has a cavity 3 in one face of partially spherical form. Laid within each cavity 3, in close conformity with the cavity, is a coil 4 of wire, preferably held in place by 25 some suitable cementitious material restraining the coil from disturbance and constituting a lining for the blocks 1 and 2. The coils 4 are connected together intermediate of their lengths by a bridge wire 5 so that 30 the coils are electrically in series. One end of one of the coils is connected by a conductor 6 with metallic strips 7 leading across the space between the two blocks and serving, in conjunction with another such strip 40 8 on the opposite side of the instrument, to hold and anchor the two blocks 1 and 2 together.

45 Lodged within the cavities 3 but spaced concentrically from the inner walls thereof, is a spherical body 9. This body is hollow with an equatorial rib 10 and truncated polar extensions 11. The exterior of the spherical body 9 is provided with a spherical winding 12, concentric with the windings 50 4 in the blocks 1 and 2, but these windings 4 and 12, though spaced apart in order to avoid mechanical contact, are within inductive range. The winding 12 extends from the rib 10 to the extensions 11.

55 The body 9 with the windings 12 constitute the rotor of the apparatus and corresponds to the movable variometer winding of the ordinary variometer structure.

Extending from diametrically opposite 60 sides of the rotor 9 are axles 13 in the form of metal tubes projecting through the intermediate spaces between the blocks 1 and 2, and journaled in the strips 7 and 8, which latter are provided with longitudinal slits 65 14, permitting the strips 7 and 8 to grip the

hollow axles 13 with sufficient force to provide such frictional contact with the axles as to hold them and the rotor 9 in any position of adjustment, but not offering sufficient mechanical resistance to prevent manipulation 70 of the rotor 9 by the fingers of the operator, the rotation of the rotor being facilitated by a knob or manipulating wheel 14^a at one end of one of the axles 13.

Extending through each axle 13, which is 75 hollow, is a sleeve or tube 15 of insulating material also extending beyond the inner end of the respective axle 13. The sleeves or tubes 15 are axially traversed by rods 16, 17, respectively projecting into the interior of the hollow rotor body 9, the rod 17 also projecting beyond the knob 14^a and carrying another knob or manipulating wheel 18, whereby the rod 17 may be turned.

Carried by the rods 16 and 17 and extending between their inner ends within the 80 rotor 9 is a coil 19 composed of a suitable number of turns of wire and constituting a vernier coil capable of rotation about the same axis as the variometer coil 12, the arrangement being such that the frictional contact between the rods 16 and 17 and the axles 13 of the variometer body 9 will cause the variometer coil 12 and the vernier coil 19 to turn together unless the knob 18 be 85 purposely turned independently, when the friction between the rods 16 and 17 and the sleeves 15 is insufficient to carry the coil 12 and the supporting body 9 with them.

The terminals of the vernier coil 19 are 90 connected by conductors 20 to the ends of the rods 16 and 17 one of which is in turn connected to a journal bearing 21 in the form of a terminal strip 22 from which current may be taken. The coils 4 are 100 coupled up in series and at one end are connected by a conductor 23 to the terminal 22, while at the other end the same coils 4 are connected by the conductor 6 to the bar 7.

The stator coils 4 are connected together 110 by the bridging conductor 5 while the coils 12 of the rotor of the variometer member are connected together by conductor 25, so as to be in series with each other and are connected up by conductors 24 to the respective axles 13.

In the particular model of the invention shown in the drawings, the current may be considered as first passing through the outside or stator winding, then through the rotor winding and then through the vernier winding and finally through the inside or second shaft 16, 17, which is insulated from the first or hollow shaft 13 by the insulating bushing 15. The vernier shaft forms a 125 steady and extended bearing for the vernier winding, which it carries, and from which connections may be made to other pieces of apparatus.

The manipulating or control buttons 14^a 130

and 18 for both the main rotor and the vernier rotor are, for convenience, located on the opposite side of the instrument from where the current is taken from the vernier winding. The hollow shaft of the main rotor carries one control button for the coarse adjustment of both the movable windings. The frictional contact between the shafts causes their common movement, when so desired, or individual movement of the vernier winding, and when the vernier winding is alone adjusted the outer or stator winding and the main rotor winding remain stationary.

15 It is contemplated, though not so shown in the drawings, to provide suitable dials and indicating arrows attached to the respective parts of the stator housing and the main rotor shaft, and also to the main rotor shaft and the vernier shaft, so that the angular positions of each winding to its adjacent winding may be observed.

Suitable means for obtaining proper friction between the shafts, such as the customary adjustable pinch binds, set screw, etc., may be employed, but are so common in practice that illustration thereof is not deemed necessary.

It is to be understood that three coils mounted on cylindrical or spherical forms are not the only embodiments of the invention, or the only manner in which the "vernier" principle may be employed, for such form has simply been selected out of many possible forms for the purpose of demonstration, since the spherically wound type is the most usual variometer in use at present. As a matter of fact the windings may be helical, spiral, toroidal, or of other form embodying the principle of vernier adjustment of the variometer, so long as such adjustment remains the same whatever form of winding be adopted, and which windings may be brought into inductive relation with each other.

Nor is it intended that the invention be restricted to a single vernier winding as representing the only possible construction, for it is entirely feasible to use any number of vernier windings to secure varying steps of inductance for particular purposes.

For the purpose of demonstrating the value of the invention, reference has been made to the reception of continuous-wave radio signals of very high frequencies, but this is not to be taken as the only manner in which the invention is to be usefully employed. The reception of radio signals of any type, damped, or undamped, modulated undamped, or telephone will be aided by the proper employment of the invention. By the word "reception" it is not intended that the invention is for use solely in tuning any particular portion of a receiver circuit to the exclusion of other por-

tions, but it is to be understood that it may be used equally well for detection, heterodyning, autodyning, regeneration, amplification, and repeating. Furthermore, while reception is suggested as the most usual 70 employment for such a delicate tuning device, the invention is equally applicable to transmitting circuits of all types, the measuring circuits of all types, and in fact for use in any electrical circuit whatever, of 75 whatever nature, in which a continuously and minutely variable inductance is desired.

The operation of the invention will be best understood by considering the instrument as composed of three coils, one of 80 which is stationary and the other two of which are collectively or independently adjustable about a single axis. The vernier coil contains a relatively small number of turns in order that a large rotation of the 85 vernier coil with respect to the movable variometer coil creates but a slight change in the total inductance of the device. The relation of the stator and rotor coils in their 90 relative movements is such that a full 180 degree rotation of the vernier coil will equal but one or two degrees of rotation of the main rotor, so that the device will permit of the selection of infinitely small values of 95 inductance within the limits of practical breadth. The number of turns of wire on the additional rotor coil or coils constituting the vernier coil is much less than the number on the main rotor so that the rotation of the additional vernier coil or coils will produce but a minute change in the total inductance of the instrument compared to the rotation of the main rotor.

What is claimed is:—

1. A device of the character described comprising a fixed coil, a second coil mounted for rotation and arranged in inductive relation to the fixed coil, and a third coil mounted for rotation and having relatively few turns as compared to the second coil, 105 said third coil being arranged in series with the second coil and in inductive relation to it.

2. A variometer comprising a series of 110 associated coils of which one is fixed in space, another is located interior to the first coil and is rotatable about an internal axis transverse to the coil and in inductive relation thereto, and another coil interior to and in series with the second coil and in inductive relation thereto, and rotatable about the same axis either with or independently of the rotation of the second coil.

3. A variometer comprising a series of 115 associated coils of which one is fixed in space, another is located interior to the first coil and is rotatable about an internal axis transverse to the coil and in inductive relation thereto, and another coil interior to and in series with the second coil and in 120

125 to and in series with the second coil and in 130

inductive relation thereto and rotatable about the same axis either with or independently of the rotation of the second coil, all of said coils having a common center of 5 rotation.

4. A variometer comprising a body portion or housing with a fixed coil therein, another coil mounted in the fixed coil for rotation about an axis corresponding to that 10 of the fixed coil, and another coil within the second coil and in series therewith and mounted for rotation about the same axis and related in number of turns to the second coil whereby it exerts a similar effect to the 15 second coil but of a minute amount as compared therewith.

5. A variometer comprising a plurality of coils, one of which is fixed, another of which is movable with respect to the fixed coil, and 20 another of which contains a relatively small number of turns and is movable with respect to either or both of the first and second named coils, said coils being respectively related so that the second and third named 25 coils are in series with each other, the second coil is in inductive relation to the first coil, and the third coil is in inductive relation to the second coil.

6. A variometer comprising a fixed outer 30 coil, an interior coil adjustable about an axis diametric of the outer coil, and a vernier coil in series with and interior to said interior coil and adjustable about the same axis as the latter, said vernier coil containing relatively few turns compared with said 35 interior coil, whereby a large movement of the vernier coil has a relatively small effect.

7. A variometer comprising a fixed outer coil, a second coil interior to the fixed coil 40 and adjustable about an axis diametric thereto, a third coil in series with and interior to the second coil and adjustable about the same axis as the second coil, and containing relatively few turns compared with the second 45 coil, whereby a large movement of the third coil has a relatively small effect, the second coil being in inductive relation to the first coil, and the third coil in inductive relation to the second coil.

8. A variometer comprising two coils in 50 inductive relation, one of said coils being fixed and the other rotatable about an axis diametric to both coils, a vernier coil adjacent to the rotatable coil, in series with, and

in inductive relation to it, and means whereby the vernier coil may be rotated with or independently of the other rotatable coil in either direction.

9. A variometer comprising an outer fixed coil having a hollow support therefor with 60 in which the coil is mounted, a hollow support and a second coil interior to and in inductive relation to the fixed coil and support, means for the rotation of the second coil and its support within the fixed coil, and a vernier coil mounted within the second-named support and in series with the second coil, said second coil and the vernier coil being mounted to rotate about a common internal 65 axis.

10. A variometer provided with an outer fixed hollow coil, an inner adjustable coil in inductive relation to the fixed coil, and a vernier coil within and in series with the adjustable coil and in inductive relation thereto, the vernier coil having an axis support traversing and frictionally held in the adjustable coil for both conjoint and independent rotation with respect thereto, whereby both coils may be moved together or may 70 be moved independently for producing minute variations of inductance by the vernier coil.

11. A variometer comprising a plurality of coils all connected in series, one of which 75 coils is fixed in space, another of which is movable with respect to the fixed coil, and another of which contains a relatively small number of turns and is movable with respect to either or both of the first and second 80 coils, said coils being respectively related so that the second coil is in inductive relation to the first coil, and the third coil is in inductive relation to the second coil.

12. A device of the character described 85 comprising primary and secondary coils in series in inductive relation and relatively movable to effect a maximum variation in the inductance, and a third coil electrically 90 in series with the secondary coil, said third coil having comparatively few turns and adjustable with respect to the secondary coil 100 to effect minute corrections in the inductance.

In testimony, that I claim the foregoing as my own, I have hereto affixed my signature.

COLEMAN MULFORD GRAY.
